UNITED STATES PATENT OFFICE

ALVA T. SMITH, OF MILWAUKEE, WISCONSIN, ASSIGNOR TO NATIONAL ENAMELING & STAMPING COMPANY, OF MILWAUKEE, WISCONSIN

DESIGN FOR AN ELECTRIC CASSEROLE

Application filed April 30, 1932. Serial No. 43,677. Term of patent 7 years.

To all whom it may concern:

Be it known that I, ALVA T. SMITH, a citizen of the United States, of Milwaukee, in the county of Milwaukee and State of Wisconsin, have invented a new, original, and ornamental Design for an Electric Casserole, of which the following is a specification, reference being had to the accompanying drawing, forming part thereof.

Figure 1 is a perspective view of the electric casserole showing my new design.

Figure 2 is a top plan view of the same, with the cover removed.

I claim:

The ornamental design for an electric casserole, as shown and described.
